(57) **CLAIM**

The ornamental design for a digital camera display screen with transitional graphical user interface, as shown and described.

DESCRIPTION

FIG. 1 is a perspective view of the digital camera, showing the new design;

FIG. 2 is a front view thereof;

FIG. 3 is a rear view thereof;

FIG. 4 is a top view thereof;

FIG. 5 is a left view thereof;

FIG. 6 is an enlarged view of a display portion, showing a first image of the display screen, shown separately for clarity;

FIG. 7 is an enlarged view of the display portion, showing a second image of the display screen, shown separately for clarity;

FIG. 8 is an enlarged view of the display portion, showing a third image of the display screen, shown separately for clarity; and,

FIG. 9 is an enlarged view of the display portion, showing a fourth image of the display screen, shown separately for clarity.

The broken lines showing the digital camera illustrate the environment of the claimed design and form no part thereof. The broken lines within the display screen in the drawings illustrate portions of the graphical user interface which form no part of the claimed design.

The subject matter in this design patent includes a process or period in which an image changes into another image. This process or period forms no part of the claimed design.
